UNITED STATES PATENT OFFICE.

FARLEY GRANGER CLARK, PAUL ACKERMAN, AND CHARLES ERNEST CANSFIELD, OF TORONTO, ONTARIO, CANADA, ASSIGNORS TO THE TORONTO POWER COMPANY LIMITED, OF TORONTO, ONTARIO, CANADA, A CORPORATION OF ONTARIO.

ELECTRICALLY-HEATED TANK OR RESERVOIR.

1,269,053.

Specification of Letters Patent. Patented June 11, 1918.

Application filed July 5, 1917. Serial No. 178,622.

To all whom it may concern:

Be it known that we, FARLEY GRANGER CLARK, a citizen of the United States of America, PAUL ACKERMAN, a citizen of

5 Switzerland, and CHARLES ERNEST CANSFIELD, a subject of the King of Great Britain, all residing at the city of Toronto, in the county of York and Province of Ontario, Dominion of Canada, have invented 10 certain new and useful Improvements in Electrically-Heated Tanks or Reservoirs; and we hereby declare that the following is a full, clear, and exact description of the same.

15 This invention relates to a tank or reservoir heated by two or more electric heater elements, either or both of which may be selectively used for raising the tank content to the required temperature, to supply 20 the normal daily demands and the increased and the urgent demands occurring periodically and at irregular intervals; the capacity of the tank and the heat-generating power of the heater elements being correctly 25 proportioned for this purpose, and the selective operation of the heaters being controlled either manually or automatically.

In carrying out the invention, one of the heater elements, which may be termed the 30 "main heater," is continuously used for heating the tank content, the capacity of the tank and the heat-generating power of this heater element being so proportioned as to satisfy the normal daily demands, such 35 continuous use obtaining the usual preferential rates for electric service. The other of the heater elements, which may be termed the "auxiliary heater" is brought into use when the tank content is required to meet 40 urgent or increased demands, the main heater element being placed so that the whole of the tank content may be uniformly heated to the required temperature, and the auxiliary heater element being placed so 45 that the upper part of the tank content may be quickly raised to the required temperature, either when in the tank, or as it flows to the discharge pipe.

In the drawings:—

50 Figures 1, and 2, are sectional elevational views of two preferred modifications of our invention.

Details of the electric heater elements and the control devices are not shown, as we

may use any type of electric heater element 55 or elements and any type of manual or thermostatic control.

1 represents a tank or reservoir which is preferably covered with heat insulation 2. 3 represents the inlet pipe entering the tank 60 or reservoir and discharging preferably near the bottom of the tank. 4 represents the outlet pipe from the tank, and 5 represents a drain pipe and cock.

A represents the main electric heater element, and B the auxiliary heater element. a', a² and b', b², respectively represent the terminals of the respective heater elements A and B.

10 and 11 represent the two line wires connecting to some source of electric power, and 12 and 13 are the connections between the line wires 10 and 11 and the terminals a' and a², respectively, of the main heater A.

14 and 15 are corresponding connections 75 to the auxiliary heater B, 14 connecting directly to the heater terminal b', and 15 connecting through the manually-controlled switch 16 or the thermostatically-controlled switch 17 to the terminal b². The control 80 switch 16 and the thermostatic switch 17 are shown shunting each other, so that the circuit of the electric heater B may be closed independently by either of the two switches.

In Fig. 1, the main heater A is attached 85 to the by-pass pipe 7, having an inlet at 6 into the side of the tank, and the auxiliary heater B is attached to a pipe 8 connecting from the by-pass pipe 7, below the heater A, to the outlet pipe 4, preferably at the top of 90 the tank.

Fig. 2 shows another method of using the electric heater elements, in which the main heater element A is arranged in the same way as in Fig. 1 and the auxiliary heater 95 element B is attached to a pipe 9 connecting from the pipe 7, above its inlet 6 into the tank, to the outlet pipe 4.

In all cases, the auxiliary heater can be controlled either manually by means of the 100 switch 16, closed at times of excessive demand, or controlled automatically by means of a thermostatic switch which will close the circuit through the auxiliary heater B at a predetermined low temperature and 105 open it when a predetermined high temperature has been attained.

These various figures indicate the prin-

- 5 principle of utilizing the main heater A to uniformly heat the whole of the tank content to a temperature which will provide a storage supply ready for constant use, to meet the normal daily demand; of utilizing the auxiliary heater B to assist the main heater A in supplying any increased demand, by quickly raising the temperature of part of the tank content; and of utilizing either a 10 thermostatic or manual device for bringing the auxiliary heater into use, the thermostatic device automatically maintaining the temperature in the top of the tank at a predetermined degree.
- 15 The heaters may be used in connection with a tank or reservoir designed for any particular purpose, and the heaters may consist of single or multiple elements.
- By arranging and operating the heaters 20 in this way, the tank content may be efficiently and economically heated to supply all reasonable normal and increased demands, the heaters and the tank capacity being proportioned to the demand.
- 25 Having thus fully described the nature of our invention, what we claim as new and desire to secure by Letters Patent, is:—

1. An electrically heated tank comprising

a by-pass pipe having an inlet into the side of the tank, a main electric heater installed on said pipe, a pipe connecting the by-pass pipe with the top of the tank, an auxiliary electric heater installed on the connecting pipe, and means controlling the circuit of the current through said heaters. 30

2. An electrically heated tank comprising a by-pass pipe having an inlet into the side of the tank, a main electric heater installed on said pipe, a pipe connecting the by-pass pipe with the top of the tank, an auxiliary 40 electric heater installed on the connecting pipe, electrical conductors for the main and auxiliary heaters, and means selectively controlling the circuit of the current to the heaters for energizing the main heater to 45 heat the entire tank content and the auxiliary heater to heat the upper portion of the tank content. 35
